TIME-CONTROLLED ACTUATING APPARATUS

Sture John Verner Örtenblad, Stockholm, Sweden

Application September 8, 1949, Serial No. 114,481
In Sweden October 15, 1948

14 Claims. (Cl. 200—37)

1

The present invention relates to time-controlled actuating apparatus for performing electrical switching operations of any kind, more particularly apparatus of the type comprising a rotative timing cylinder, i. e. a cylinder which is caused to rotate in dependence upon the time, which cylinder, or at least the peripheral zone of which, consists of an electrically conducting material and has one or more contacts attached there-to in different positions in accordance with the timed instants of any desired switching operation, and comprising also a counter-contact so provided that the contacts of said cylinder are allowed to engage said counter-contact in dependence upon the rotation of said cylinder.

One object of the invention is to provide an actuating apparatus for opening and closing electric circuits at arbitrarily timed instants which apparatus is of a simple and reliable design and is easy to attend.

Another object of this invention resides in the provision of a time-controlled actuating apparatus which may be set to accomplish switching operations at certain desirable instants during a longer period of time, e. g. to allow all switching instants to be set in advance for a whole week at a time, even when different switching instants are desired for each day.

A further object of this invention is to provide an embodiment of said apparatus, which after the switching instants have been accordingly set, e. g. for one week, at the end of that week may be caused to act still a further week, or longer, at unvaried setting merely in response to the actuation of a single handle.

A feature of the invention comprises a time-controlled actuating apparatus of the type set forth, in which the timing cylinder is provided with a number of peripheral grooves, viz. one or several such grooves, into which contact balls may be fastened jammingly in different positions along the periphery in accordance with the instants of any desired switching operation.

Another feature of the invention comprises a time-controlled actuating apparatus of the type set forth, in which the timing cylinder is provided with a plurality of parallel grooves, and contact balls may be fastened jammingly in each such groove in positions corresponding to the instant of any desirable switching operation, whereas the counter-contact is adapted to be displaced step by step to a position opposite any of the various grooves in correspondence with the date or day of the switching operation desired.

In accordance with this last-mentioned feature the counter-contact may be mounted on a

2

slide which is movable in parallel with the timing cylinder, which slide is displaceable step by step by said timing cylinder dependent upon its rotation, each step corresponding to the spacing between the individual grooves.

In accordance with this feature said slide may be associated with a spring mechanism for its homing and may support a ball magazine and a ball feeding assembly adapted to force balls into the grooves of said timing cylinder.

The time-controlled actuating apparatus according to this invention may be designed either as a self-contained actuating equipment incorporating a connecting cable length for connection to a wall socket and also an outlet contact socket into which may be plugged-in the connecting cord of a machine or apparatus to be controlled, e. g. a radio receiver, electric heater, instrument or the like, or even be assembled to one unit with a controlled apparatus, particularly in cases that such apparatus is a radio set.

The foregoing and further objects and features of the invention will appear readily from the following description of one exemplary embodiment 25 of an actuating apparatus according to this invention, when taken in conjunction with the accompanying drawings, in which:

Figs. 1-12 illustrate an actuating apparatus according to the invention, which is designed as a self-contained actuating equipment and intended to perform connection and disconnection of another apparatus at recurrent instants in the course of one week.

Fig. 1 is an elevational view as seen from the front, Fig. 2 is an elevational rear view, and Fig. 3 is a side view as seen in the direction indicated by the arrows III in Figs. 1 and 2.

Figs. 4 and 5 show two horizontal sections taken substantially on the lines IV—IV and V—V, respectively, of Fig. 2 (see also Fig. 1), while Fig. 6 is a vertical section substantially taken on the line VI—VI of Fig. 4.

Fig. 7 shows a vertical section along the line VII—VII of Fig. 1. Fig. 8 illustrates a vertical section taken on the line VIII—VIII of Fig. 6; Fig. 9 is a sectional view along the line IX—IX of Fig. 6; Fig. 10 shows a partial section taken on the line X—X of Fig. 9, while Fig. 11 is a partial section taken on the line XI—XI of Fig. 9.

Fig. 12 is a perspective view of the means for automatically disconnecting the controlled apparatus at the end of a certain adjustable period of time.

Fig. 13 is a circuit diagram for the actuating apparatus shown in Figs. 1-12.

Fig. 14 is a perspective view on a reduced scale

of a radio set which is combined in a single unit with an actuating apparatus according to this invention as illustrated in Figs. 1-13.

The actuating apparatus shown in Figs. 1-12 is provided with a housing in form of a rectangular box 1. The elevational view in Fig. 1 may be regarded as the front, while the elevation according to Fig. 2 is the rear. The essential parts of the actuating apparatus are mounted on a substantially U-shaped frame 2 of sheet-metal, to which is attached a supporting member 3, likewise of metal, as clearly shown particularly in Fig. 4. Members 2 and 3 constitute a rack which in combination with the actuating equipment parts mounted thereon is inserted into the box 1 from its rear, and then the rear wall is screwed on to the box.

The rear wall 4 has a circular aperture for the timing cylinder 5 rotatively mounted on a shaft 6, in turn rotatively supported in the member 3. A clock-work 7, which conveniently may be equipped with a dial 3 and pointers 9 visible through a circular opening in the front wall of the box, so that this assembly simultaneously may serve as a clock, is located between the supporting member 3 and the portion of the frame 2 adjacent the front wall of the box. The drive spindle 10 which projects through the rear flange of the clock-work 7 should be geared to the speed of the hour-hand, said spindle being coaxially aligned with the shaft 6 and coupled therewith, so that said shaft is driven at the same speed as the hour-hand.

The timing cylinder 5 supports a securely mounted rotary knob 11 of insulating material. The rearwards turned side of the rotary knob 11 has a recess 12 in which is disposed a frictional coupling between the shaft 6 and the timing cylinder 5. This frictional coupling is made of a curved leaf spring 13 with a central opening through which the shaft 6 freely projects, said spring being strained between a collar head 14 at the end of shaft 6, on the one hand, and the end surface of the timing cylinder 5 on the other hand. Such frictional coupling transfers torque from the hour-hand spindle 10 through the shaft 6 to the timing cylinder 5, but no rotation from the rotary knob 11 and the timing cylinder 5 to said shaft 6. The timing cylinder 5 may thus be turned by means of the knob 11 without affecting the clock-work. A clock dial scale (graduated for 12 hours) is fixed on the rotary knob 11, while an index 16 is attached to the stationary rear wall 4 adjacent the peripheral rim of said rotary knob, or vice versa.

The timing cylinder consists of an electrically conducting material; aluminium is preferred, although also copper or iron may be used. The timing cylinder is provided with a plurality of peripheral grooves 20, that is, one groove for each 12-hour time interval, hence, a total of fourteen grooves, since the actuating apparatus set forth herein is intended to be set for accomplishing switching operations during a whole week at a time. Contact balls 21, suitably of steel, are adapted to be jammed into the grooves 20 in positions dependent upon the instant at which the desired switching operation shall take place. Some such balls 21, fixed by jamming, are shown in Figs. 4 and 6, and an arbitrary number of balls 21 may be fastened by jamming in each groove 20 as required. It may be mentioned by way of an example relating to the relative dimensions of the grooves 20 and the balls 21, that in conjunction with a ball diameter of

3 millimeters, a groove width of 2.95 millimeters, a groove depth of 1.75 millimeters and a partition width of .55 millimeter between adjacent grooves have proved satisfactory.

The counter-contact 22 which co-operates with the balls jammingly fixed on the timing cylinder is mounted on a slide 23 which is movable in parallel with the timing cylinder and which slides on a transverse beam 24 of U-shaped cross section fixed in the frame 2; see particularly Figs. 4, 6 and 8. The counter-contact is made of a leaf spring 22, the one end of which is fixed on the slide 23 consisting of a plastic, while its tapered end 22' is bent in a direction towards a point on the timing cylinder located immediately above the horizontal central plane through the timing cylinder. The end of the leaf spring 22 pointing towards the timing cylinder is provided with an inclined surface 22'' which co-operates with a set-screw 26 for so adjusting the contact point 22' vertically, that the contact closing operation, if desired, may be timed to take place a short moment earlier (or later) than the instant to which the timing cylinder actually has been set.

Displacement of the slide 23 is achieved by the timing cylinder during its rotation. To this end the surface of the slide facing the timing cylinder is provided with a group of inclined laminae 28, the number of which corresponds to the number of grooves 20 in the timing cylinder, which latter carries a radially projecting pin 29 which is adapted to co-operate with the laminae 28 one after the other and to advance the slide 23 one step in response to each revolution of the timing cylinder. The pin 29 is fixed in a position near the innermost end of the timing cylinder (at the upper end according to Fig. 4), while the slide 23 has its initial position at the upper end of Fig. 4 (to the left in Fig. 8). The timing cylinder is driven by the clock-work in the direction indicated by the arrow P in Fig. 6. During each revolution of the timing cylinder the pin 29 is caused to pass along one lamina 28 (along the left lamina edge in Fig. 8), whereby the slide 23 is forced to the right in Fig. 8, i. e. towards the rear of the actuating apparatus, due to the resulting wedge-effect.

When the slide 23 after one week and in response to the action of the timing cylinder has been advanced to the position shown in Figs. 8 and 9, its automatic homing is required. To this end a resetting rod 31 is provided, which extends inside the transverse U-shaped beam 24, from the front of the actuating apparatus, where it carries an actuating knob (push-button) 32 projecting through the front wall, to the rear of said apparatus, where said rod is formed with a first projection 31' for imparting homing motion to the slide and also with a second projection 31'' for hooking the resetting rod 31 in engagement with a latch member 33. The end of the resetting rod 31 adjacent the rear of the actuating apparatus is bent back in the direction towards the front of the actuating apparatus so as to form a hook for a tension spring 34, the opposite end of which is fixed in the frame 2 adjacent the front wall of the apparatus. The latch member 33 consists of a spring of a shape similar to that of a hair-pin, the upper leg of which is fixed in the transverse beam 24, while its lower leg engages downwards open recesses in the lower edges of the transverse beam 24 (see Figs. 8, 9 and 11). The resetting rod 31 may thus be pressed inwards for one week at a time by means of the push-button 32, thereby tensioning the re-

storing spring 34. The rod 31 is then by means of its detent 31" hooked in engagement with the lower leg of the latch member 33, and the end of said rod rests in an aperture in the rear of frame 2.

The slide 23 supports a release lever 36 (Figs. 6 and 8) for the resetting rod 31, which lever is located under the slide and pivotally mounted at 37. Said lever 36 carries an arm 36' which moves in over the lower leg of the latch member 33 when the slide approaches its extreme right position in Figs. 8 and 9. The opposite arm of release lever 36 is provided with a projection 38 which is actuated by the pin 29 at the innermost end of the timing cylinder when the slide occupies the last mentioned position. It is understood that the timing cylinder makes one revolution after the pin 29 has engaged the last lamina 28 and that the engagement between pin 29 and projection 38 occurs at the end of said last revolution. The lower leg of latch member 33 is accordingly urged down and out of engagement with the detent 31" on the resetting rod 31 which, due to the action of the released spring 34, is rapidly pushed out a given length through the wall of the actuating apparatus. Since the engagement between the resetting rod 31 and the slide 23 thereby remains active (at detent 31'), the slide is pulled back to its initial position at the front end of the actuating apparatus (at the left according to Figs. 8 and 9).

The push-button 32 and the portion of the resetting rod 31 projecting beyond the front wall of the actuating apparatus indicate that the mechanism again must be tensioned. The single step required is thus to press the resetting rod 31 in engagement with the latch member 33 in order to restore the slide 23 after a further week has elapsed. In general, however, the operator will hardly find an opportunity immediately to depress the resetting rod 31 after it has been launched out beyond the face of the actuating apparatus, and in order still to allow the timing cylinder to advance the slide 23 without being obstructed due to presence of the detent 31' on the resetting rod, this rod should be raised out of engagement with the slide after the latter has been homed. To this end the transverse beam 24 is provided with a stop pin 39 which in cooperation with the oblique portion 31" of rod 31 is raising the rod 31 at the termination of its return motion.

The balls 21, which are adapted to be jammed into the grooves 20 of the timing cylinder, are delivered from a ball magazine 41 at the top of the slide 23 (Figs. 6 and 9). The bottom of this magazine is slanting towards one end of the slide—the right end according to Fig. 9—where a vertical outlet 42 (Figs. 4 and 6) is provided for the individual balls. This outlet emerges in a horizontal rectangular guide aperture 43 (Fig. 9) in which is axially movable a rectangular guide envelope 44, in which a plunger 45 (Figs. 6 and 10) is mounted so as to be axially displaced for feeding one ball at a time to the grooves of the timing cylinder. In order that no balls spontaneously may fall out from the space in front of the plunger 45 as defined by the guide envelope 44, a weak spring arrester 46 is provided in the manner indicated in Fig. 10.

The plunger 45 is operated manually by means of a manipulation knob 47 (Figs. 1 and 5) through a mechanism now to be described. Said manipulation knob 47 and its supporting shaft 48 are rotatively (and axially movably) mounted

in the front wall of the apparatus and in a bearing block 49 which is fixed on the bottom of box 1. The shaft 48 carries a sleeve 50 which is locked against rotation (but axially movable) and which supports an upwards pointing projection 51. This projection is linked by a pull-rod 52 to a substantially vertical lever 53 in form of a plate or metal slab. The lower end of this lever-plate is pivotally mounted at 54 in the frame 2, while its upper end under the action of a torsional spring 55 resiliently abuts on that portion of frame 2 which is located behind the plunger 45. Turning of the manipulation knob in the clock-wise direction as viewed in Fig. 1 (counter-clockwise as seen in Fig. 6) causes the lever-plate 53 to act upon the rear end of the connecting rod 45' of plunger 45, so that this plunger 45 is forced forward.

The plunger 45 cooperates with the guide envelope 44 through a comparatively rigid spring 57 (Figs. 6 and 10), e. g. a piano cord, which is bent substantially to U-shaped configuration with one end (the right in Fig. 6) anchored in the connecting rod 45' and the other end formed like an eyelet freely encompassing said connecting rod and abutting against the rear end of the guide envelope 44. Hence, the plunger 45 and the guide envelope 44 are initially advanced as one unit, until the front end of the guide envelope comes to rest against the timing cylinder, in which moment the resistibility of spring 57 is overcome with the result that the plunger 45 is advanced additionally relative to the guide envelope 44, which now acts as the guiding member for the ball in front of the plunger 45, until this ball has been squeezed into the groove proper of the timing cylinder. Thence the guide envelope and the plunger are reset to normal position by a restoring spring 58, the one end of which is attached to the rear end of envelope 44, while its opposite end is fixed on the slide 23 (Fig. 10). It is anticipated that spring 58 is considerably weaker than spring 57.

The slide 23 is adapted to occupy various different positions along the timing cylinder, these positions depending upon the date or day and its antemeridian or post meridian hours, respectively. The position of the slide is indicated by means of a longitudinal scale 60 (Figs. 4 and 6) attached thereto and having fourteen narrow rectangles marked thereon. The first rectangle (as reckoned from below in Fig. 4) is designated "Mond," on a white background, for example, and denotes the antemeridian hours of the first day which may be Monday. The second rectangle is likewise designated "Mond," e. g. on a black bottom, and denotes the post meridian hours of said first day. The same relates to the succeeding rectangles which are marked in pairs as "Tuesd," "Wednesd," "Thursd," "Frid," "Saturd" and "Sund," respectively. A stationary cover plate 61 with an indexing aperture 62 provided therein (see also Fig. 3) is overlaying the scale 60 and secured in the frame 2, for instance. The plate 61 and its aperture 62 are rendered visible through a window 63 provided in the corresponding lateral wall of the apparatus as illustrated in Fig. 3. Fig. 3 also visualizes the "Sund" designated rectangle as displayed in the aperture 62. Moreover, the timing cylinder and its grooves may readily be observed through the window 63.

In order to remove the balls from the grooves 20 of the timing cylinder, a scraper member 65 (see Figs. 6 and 8 as well as Fig. 3) is disposed

alongside the timing cylinder just above the ball magazine 41, which scraper member carries as many fingers as grooves are provided on the timing cylinder, each of these fingers occupies a position exactly opposite its corresponding groove 20. The scraper member 65 is pivotally mounted by means of a spindle extending in parallel with the timing cylinder between a support 67 of the cover plate 61 and the frame 2, said spindle being fitted with a tilt-knob 68 accessible from the rear of the actuating apparatus. The scraper member is made of a sheet-metal strip bent to cup-shaped configuration and having said fingers formed by stamping at its edge facing the timing cylinder. The bottom of this scraper member has an orifice 66, and immediately under this orifice a corresponding orifice 69 is provided in the cover plate 61. The relative positions of the orifices 66, 69 are shown in Figs. 4 and 8. It may be derived from the drawing that the orifices 66, 69, instead of being aligned, are slightly displaced with respect of each other in their positions shown, so that the balls are prevented from escaping the ball magazine even if the apparatus should be turned up and down. The fingers of the scraper member 65 may be tilted in engagement with the grooves 20 of the timing cylinder, whereupon the timing cylinder may be rotated clockwise (in opposition to the direction indicated by the arrow P in Fig. 6) by turning the rotary knob 41, whereby all balls on the timing cylinder are loosened and thus caused to drop down into the cup-shaped scraper member for further conveyance to the ball magazine on account of the present aligned relation of the two orifices 66, 69. Spring locking means may be provided for both extreme positions (angular positions) of the scraper member 65, but no such means being illustrated as they do not form part of the invention and may easily be provided by each one skilled in the art.

Prior to the disclosure of the electrical outfit of the actuating apparatus it is deemed convenient briefly to elucidate the manner according to which the above described and chiefly mechanical arrangements may be used and how they operate. The slide 23 is assumed to occupy its initial position (at the top according to Fig. 4). Then, by means of the rotary knob 41, the timing cylinder may be turned counter-clockwise as viewed in Fig. 2 (in the direction indicated by the arrow P in Fig. 6) until the index 16 opposes the time designation on scale 15 according to which the first switching procedure shall take place. In this position of the timing cylinder the rotary knob 47 is turned clockwise as viewed in Fig. 1, whereby a contact ball is jammed into the first groove of the timing cylinder at the corresponding circumferential point thereof. It is thus possible by sequentially turning the knob 41 in accordance with the corresponding time designation and by recurrent manipulations of the rotary knob 47 to fix one ball after the other in accordance with the entire number of switching instants desirable in the course of one week. Thereafter, when the timing cylinder is under the action of the clock-work, the counter-contact 22 on the slide 23 will accordingly make contact with one ball after the other in their positions on the timing cylinder.

The circuit diagram according to Fig. 13 shows the electrical outfit of the actuating apparatus. The timing cylinder 5 of electrically conducting material is directly connected to the metallic rack of the actuating apparatus, to which is also

connected the negative terminal of a battery B. A conductor 71 interconnects the counter-contact 22 and one end of a relay winding 72, the opposite end of which is associated with a contact point 13 with which the break contact 74 on the relay armature 75 makes contact in the back-position (normal position) of the latter. A conductor 76 connects this break contact 74 with the positive terminal of the battery B. The armature 75 which is pivoted at 77 carries a mercury switch 78 for the operating circuit, the two conductors of which, i. e. 79, 80, are extended through the box of the apparatus as indicated at 1, in form of a connecting cord (flex) 81 which is terminated by a plug-in device 82 for insertion into a wall socket. One of said conductors, i. e. conductor 80, is provided with and connected to an outlet contact sleeve 83 projecting through an opening in the rear wall of the apparatus and adapted to receive the plug 84 terminating the connecting cord of an apparatus to be controlled, e. g. the cord of a radio set or an electric heating device.

At each occasion when a contact ball 21 on the timing cylinder makes contact with the counter-contact 22, a circuit is established through the relay winding 72, whereby the armature 75 is attracted and the operating circuit 79, 80 is closed in the mercury switch 78 when tilted out of the position shown, so that the controlled apparatus is switched in circuit. The path through the relay winding is simultaneously opened at 73, 74 in order to avoid undue consumption of battery energy. Moreover, the battery may manually be switched in circuit and disconnected by means of a switch member 86 forming part of the path through the relay winding, so that the battery may be disconnected when the apparatus is not in use. In order to allow the controlled apparatus to be switched in circuit by hand independently of the timing cylinder, the actuating circuit, in which the relay winding and the battery are involved, is connected to a normally open shunt path 87 across the timing cylinder and the counter-contact. This shunt path, moreover, is connected to the metallic rack of the apparatus and includes a contact point which may be closed, when desired, by means of a switch 88 suitably in form of a push-button. Disconnection of the controlled apparatus at the end of a given period 50 of time may be achieved by depressing the manually actuated mechanical member 89 which is adapted mechanically to restore to normal the relay armature 75 and the mercury switch 78 fixed thereon. However, it is also possible to utilize a member which is adjustably fitted on the timing cylinder for restoring the relay armature to its position of rest after the elapse of a predetermined period of time. Circuit breaking means of this nature are disclosed hereinafter subsequent to the more detailed explanation of the electrical outfit forming part of the actuating apparatus per se.

As clearly illustrated in Fig. 7, the battery B may be an ordinary pocket-lamp battery or cell. Its negative terminal strip abuts on a connector member 91 attached to the frame 2, while its positive terminal strip is connected to the break contact 74 of the relay assembly. The conductors forming part of the control circuit are not shown in Figs. 1-12, but their provision will be readily understood by comparison with Fig. 13. The relay assembly parts are shown particularly in Figs. 5, 6 and 7. The relay armature 75 is made up of a sheet-metal strip which is bent to the configuration of an inverted U

and having its limbs projecting downwards and pivotally mounted at 77 in the U-shaped relay frame 93. The top face of the relay armature 75 supports a resilient holder 94 for the mercury switch 78 incorporating the conductor pair 79, 80 of the operating circuit in form of a cord. Adjacent the end where the conductors 79, 80 enter the mercury switch 78, the relay armature 75 is formed with an integral lateral projection 95, the downwards pointing flange of which presents an inclined surface 96 for co-operation with a corresponding oblique surface 97 of a leaf spring 98 which is secured to the frame 2. This leaf spring may be actuated by the push-button 89 in such a manner that the relay armature 75 is set to the position shown in Figs. 6 and 13 in response to this push-button 89 in its depressed state. The leaf spring 98 also constitutes the resetting means for the push-button 89.

The switch 86 for connecting and disconnecting the battery is suitably operated by using the contact ball positioning knob 47 (Fig. 5) which just by this reason is made axially movable. The shaft 48 carries at its end projecting beyond the bearing block 49 a sleeve 101 of insulating material with a metal ring 86 provided therein for co-operation with two contact springs 71', and constitutes accordingly the movable contact element of said switch. The contact springs 71' are fixed on a slab 102 of insulating material. The contact ring 86 is formed with a circumferential channel which is adapted to receive the ends of contact springs 71' so as to provide a resilient latch for the axially movable shaft 48 when depressed by means of the knob 47. It is thus obvious that the knob 47 always has to be depressed when the actuating apparatus is in use, in order to keep the switch 86 closed. With the knob 47 in its outermost position the contact springs 71' rest in a groove formed in a projection of the insulating sleeve 101, in which case the switch 86 is open.

The switch 86 for manually connecting the controlled apparatus in circuit by closing the shunt path 87 is disposed particularly as shown in Fig. 5. A contact spring 104 associated with one of the contact springs 71' and fixed on a slab 105 of insulating material on the frame 2 may be operated by the push-button 88 and thus caused to engage a contact member 106 attached to the frame 2. It is thereby possible by depressing the push-button 88 to apply a current impulse through the relay winding 72 and, hence, to connect the controlled apparatus in circuit by the aid of the mercury switch 78. Also in this case a manual disconnection of the controlled apparatus may be accomplished by means of the push-button 89.

The contrivance for automatically disconnecting the controlled apparatus at the termination of a given adjustable period of time is illustrated and set forth with particular reference to Figs. 4 and 12. The essential actuating member is a ring 107 which is angularly adjustable on the timing cylinder and provided with a radial projection in form of a pin 108 and an axial projection in the shape of a plate 109a. The plate 109a carries a hinged latch or clip member 109b, the apex of which constitutes an index 109'. The ring 107 is adjustable to any arbitrary angular position relative to the timing cylinder by reference to the time scale 15 on the rotary knob 11 and said index 109' on the clip member 109b, and may be locked in any desired position by clamping the clip member 109b against the rim of the rotary knob 11, as shown in the drawing,

when an automatic disconnection is desirable, while the clip member 109b otherwise will be swung away from the vicinity of said rim. In order to avoid that the ring follows the movement of the timing cylinder under the action of the clock-work, a stationary stop pin 110 is provided at the rear wall. This pin obstructs movement of the ring 107 due to the fact that the radially projecting portion of the clip member 109b comes to rest on said pin 110.

The pin 108 is adapted to actuate the relay armature 75 through a lever assembly or similar system, when the ring 107 is locked to the timing cylinder by means of the clip member 109b. In the embodiment illustrated, a crank-lever 111 with two arms is pivoted in two stationary bearings 112 secured to the frame 2. One of these lever arms co-operates with the pin 108 of the timing cylinder ring 107, while the other lever arm is adapted to co-operate with an upwards projecting arm 113 on the relay armature 75 in such a manner, that the relay armature becomes tilted from its attracted position (Fig. 12) to its released or normal position (Figs. 6 and 13) when the pin 108 engages the first-mentioned arm.

The ring 107 may be set subsequent to each finally accomplished connection of the controlled apparatus, if an automatic disconnection is desired at the termination of a given period of time, and this is particularly advantageous in cases when the controlled apparatus is an electric water heater or similar heating device. However, the ring may also be set in advance for one selected switching operation for a 12 hour period. It is obvious that the ring 107 and its associated implements may be omitted if the actuating apparatus is not intended to perform automatic disconnection of the controlled apparatus.

The actuating apparatus may obviously also be employed for producing an acoustic signal at predetermined instants if the relay armature be arranged to initiate any arbitrarily chosen acoustic signal emitter. Such an arrangement is disclosed in the exemplary embodiment set forth, simply by providing the relay armature 75 with an upwards extending arm 113, the upper end of which carries a clapper 114 for co-operation with a sound emitter 115. It will be clear that this signal emitter produces an attention signal of short duration at the circuit closing instant, but signalling devices producing acoustic signals of longer persistence, such as a common trembler bell, may also be employed.

The connecting cord 81 and the outlet socket 83 are arranged in one and the same wall of the box (the rear wall) which also supports the timing cylinder rotary knob 11 with its time scale 15 thereon and the tilt-knob 68 for the scraper member 65. The contact ball positioning rotary knob 47 as well as the push-buttons 89, 88 and 32 for restoring the relay armature by hand, for manually closing the actuating circuit, and for manually straining the resetting spring, respectively, have been arranged on the opposite wall (the front wall) of the box, although it is understood that numerous modifications are possible.

It is thus evidenced that the actuating apparatus according to this invention may be set in advance so as to accomplish a great number of switching operations in the course of one week (or during still longer time intervals, if the apparatus is accordingly designed). If no changes are needed from one week to another, only the resetting spring requires renewed straining at the end of each week, and this is the sole manual

operation required, e. g. in the course of one year or even still longer. The provision of two complete revolutions of the timing cylinder for each twenty-four hour periods allows, in addition to a more precise setting, also the application of an ordinary clock dial to the rotary knob of the timing cylinder, since, as a matter of fact, this cylinder rotates with the speed of the hour-hand. All manually operated knobs and push-buttons are accessible from the exterior of the box, while the latter is wholly closed in all other respects.

In general, there will scarcely be any need for modifying the setting of the actuating apparatus, but if such modification should be required, this may readily be accomplished by removing the contact balls from their positions on the timing cylinder and then to squeeze the balls into revised positions while the timing cylinder successively is set in accordance with the new switching instants wanted, while the time proper is indicated by means of the clock dial on the rotary knob of the timing cylinder and the day is rendered visible on the day indicating scale through the window in one of the lateral walls of the actuating apparatus.

Although the foregoing description of one exemplary embodiment of this invention relates to a self-contained actuating apparatus, it will readily be understood that the actuating apparatus according to the invention likewise may be combined with the controlled apparatus so as to form a single unit, e. g. be mounted in the box of a radio set, if such controlled apparatus is a radio receiver, for instance.

A modification of this type is illustrated in Fig. 14. It is understood that the operating circuit under the control of the relay winding is associated with the connecting cord of the radio set (not shown in Fig. 14) and that the various rotary knobs and push-buttons are attached to the walls of the radio set, preferably to the front wall.

In Fig. 14, the reference numerals 11, 32, 47, 63, 68, 88 and 89 designate the same elements, as in Figs. 1-12. As illustrated in Fig. 14, the push-button 32 for straining the resetting spring has been provided on the same side as the further manipulation means. The reference numeral 128 in Fig. 14 denotes the control means of the radio set.

Also the radio set may be provided with a specific outlet contact socket which corresponds to the outlet socket 83 of the actuating apparatus shown in Figs. 1-12, so that an electric water heater or the like may be connected thereto.

The top surface of the actuating apparatus may be provided with a sheet of such known material that it will be possible to write on it by means of a pencil or stylus for making notations relating to the instants to which the actuating apparatus has been set. Alternatively, a notation device comprising a sliding material (a sliding sheet or a sliding strip capable of receiving notations made by pencil or stylus) of well-known type may be provided for the same purpose beneath the apparatus.

As mentioned in the foregoing, the timing cylinder with the contact balls thereon may, however, be observed through the window in one of the lateral walls, whereby the positions of the balls and, accordingly, also the corresponding switching instants, may be defined by the aid of an annular clock dial scale located at the inner end of the timing cylinder and a day scale on the scraper member. Such provisions have

not been illustrated as being easy to design by each one skilled in the art.

An incandescent lamp may be arranged in the box in any suitable location so as to form part of the operating circuit for illuminating the interior of the actuating apparatus.

What I claim is:

1. A time-controlled actuating apparatus for performing electric switching operations, comprising, in combination, a rotative timing cylinder composed of an electrically conducting material at least in its peripheral zone, said cylinder having a peripheral groove formed therein, extending around said cylinder, a contact ball to be fastened jammingly in said groove, in different positions along the periphery in accordance with the instants of any desired switching operation, and a counter-contact in a position allowing contact ball jammed into said groove, to engage said counter-contact in dependence upon the rotation of said cylinder.

2. A time-controlled actuating apparatus for performing electric switching operations, comprising, in combination, a rotative timing cylinder, composed of an electrically conducting material at least in its peripheral zone, said cylinder having a plurality of parallel peripheral grooves formed therein, extending around said cylinder, contact balls to be fastened jammingly in the same, in different positions along the periphery in correspondence with the instants of any desired switching operation, and a counter-contact movable step by step to a position opposite the different grooves in accordance with the date of any desired switching operation, for allowing contact balls jammed into said grooves, to engage said counter-contact in dependence upon the rotation of said cylinder.

3. A time-controlled actuating apparatus for performing electric switching operations, comprising, in combination, a rotative timing cylinder, composed of an electrically conducting material at least in its peripheral zone, said cylinder having a plurality of parallel peripheral grooves formed therein extending around the same, contact balls to be fastened jammingly in said grooves, in different positions along the periphery corresponding to the instants of any desired switching operation, there being one groove for each 12-hour period, a slide movable in parallel with said cylinder and being displaceable step by step in response to the rotation of said cylinder, each step corresponding to the interspace between the individual grooves, and a counter-contact mounted on said slide for allowing contact balls jammed into said grooves to engage said counter-contact in dependence upon the rotation of said cylinder.

4. A time-controlled actuating apparatus for performing electric switching operations, comprising, in combination, a rotative timing cylinder, composed of an electrically conducting material at least in its peripheral zone, said cylinder having a plurality of parallel grooves formed therein extending around said cylinder, contact balls to be fastened jammingly in said grooves, in different positions along the periphery corresponding to the instants of any desired switching operation, there being one groove for each period of a plurality of time periods, a slide movable in parallel with said cylinder and being displaceable step by step in response to the rotation of said cylinder, each step corresponding to the interspace between the individual grooves, and a counter-contact mounted on said slide for

allowing contact balls jammed into said grooves, to engage said counter-contact in dependence upon the rotation of said cylinder, a magazine for contact balls, provided on said slide, and hand-operated means for inserting contact balls into the grooves of said cylinder.

5. A time-controlled actuating apparatus for performing electric switching operations, comprising, in combination, a rotative timing cylinder, composed of an electrically conducting material at least in its peripheral zone, said cylinder having a plurality of parallel grooves formed therein, extending around said cylinder, contact balls to be fastened jammingly in said grooves, in different positions along the periphery corresponding to the instants of any desired switching operation, there being one groove for each period of a plurality of time periods, a slide movable in parallel with said cylinder and being displaceable step by step in response to the rotation of said cylinder, each step corresponding to the interspace between the individual grooves, a counter-contact mounted on said slide for allowing contact balls jammed into said grooves, to engage said counter-contact in dependence upon the rotation of said cylinder, a magazine for contact balls, provided on said slide, a hand-operated plunger for inserting contact balls into the grooves of said cylinder, and a guide envelope for said plunger, which guide envelope is mounted slidably in said slide for advancement for engagement with said cylinder before said plunger effectively has inserted a ball into a groove of said cylinder.

6. A time-controlled actuating apparatus for performing electric switching operations, comprising, in combination, a rotative timing cylinder, composed of an electrically conducting material at least in its peripheral zone, said cylinder having a plurality of parallel grooves formed therein extending around said cylinder, contact balls to be fastened jammingly in said grooves, in different positions along the periphery corresponding to the instants of any desired switching operation, there being one groove for each period of a plurality of time periods, a slide movable in parallel with said cylinder and being displaceable step by step in response to the rotation of said cylinder, each step corresponding to the interspace between the individual grooves, a counter-contact mounted on said slide for allowing contact balls jammed into said grooves to engage said counter-contact in dependence upon the rotation of said cylinder, a magazine for contact balls, provided on said slide, a plunger for inserting contact balls into the grooves of said cylinder, a guide envelope for said plunger, which guide envelope is mounted slidably in said slide for advancement into engagement with said cylinder before said plunger effectively has inserted a ball into a groove of said cylinder, a resetting spring acting upon said guide envelope, a spring member interconnecting said plunger and said guide envelope, said spring member being stronger than is the resetting spring, a lever for advancing said plunger and guide envelope, and means for manual operation of said lever.

7. A time-controlled actuating apparatus for performing electric switching operations, comprising, in combination, a rotative timing cylinder composed of an electrically conducting material at least in its peripheral zone, said cylinder having a plurality of parallel grooves formed therein, extending around said cylinder,

der, contact balls to be fastened jammingly in said grooves, in different positions along the periphery of the cylinder corresponding to the instants of any desired switching operation, 5 there being one groove for each period of a plurality of time periods, a slide movable in parallel with said cylinder and being displaceable step by step in response to the rotation of said cylinder, each step corresponding to the interspace between the individual grooves, a counter-contact mounted on said slide for allowing contact balls jammed into said grooves, to engage said counter-contact in dependence upon the rotation of said cylinder, a magazine for contact balls, 10 provided on said slide, a hand-operated plunger for inserting contact balls into the grooves of said cylinder, a scraper member for removing balls from said cylinder, which scraper member is mounted alongside said cylinder and directly 15 above said ball magazine, scraper fingers, formed on said scraper member in correspondence with the grooves of said cylinder, means on said scraper member for conveying the removed balls to said ball magazine, and means for manual 20 operation of said scraper member.

8. A time-controlled actuating apparatus for performing electric switching operations, comprising, in combination, a rotative timing cylinder composed of an electrically conducting material at least in its peripheral zone, said cylinder having a plurality of parallel grooves formed therein, extending around said cylinder, contact balls to be fastened jammingly in the said grooves, in different positions along the periphery corresponding to the instants of any desired switching operation, there being one groove for each period of a plurality of time periods, a slide 30 movable in parallel with said cylinder and being displaceable step by step in response to the rotation of said cylinder, each step corresponding to the interspace between the individual grooves, a counter-contact mounted on said slide for allowing contact balls jammed into said grooves, to engage said counter-contact in dependence 35 upon the rotation of said cylinder, a magazine for contact balls, provided on said slide, a hand-operated plunger for inserting contact balls into the grooves of said cylinder, a resetting rod for said slide, a spring for causing said rod to reset 40 said slide from its extreme advance position 45 when tensioned, and means for straining said spring each time said slide has occupied said extreme position.

9. A time-controlled actuating apparatus for 55 performing electric switching operations, comprising, in combination, a rotative timing cylinder composed of an electrically conducting material at least in its peripheral zone, said cylinder having a plurality of parallel grooves formed 60 therein, extending around said cylinder, contact balls to be fastened jammingly in said grooves, in different positions along the periphery corresponding to the instants of any desired switching operation, there being one groove for each period of a plurality of time periods, a slide 65 movable in parallel with said cylinder and being displaceable step by step in response to the rotation of said cylinder, each step corresponding to the interspace between the individual grooves, a counter-contact mounted on said slide for 70 allowing contact balls jammed into said grooves, to engage said counter-contact in dependence upon the rotation of said cylinder, a magazine for contact balls, provided on said slide, a hand-operated plunger for inserting contact balls into 75

the grooves of said cylinder, a resetting rod for said slide, a spring for causing said rod to reset said slide from its extreme advance position when tensioned, means for straining said spring each time said slide has occupied said extreme position, and a stationary stop member in a position for displacing said resetting rod out of engagement with said slide at the termination of its return motion, for allowing said slide immediately to start a new advance stroke under the action of said timing cylinder.

10. A time-controlled actuating apparatus for performing electric switching operations, comprising, in combination, a clock-work having an hour-hand spindle, a shaft mounted coaxially with said spindle, a cylinder mounted rotatively on said shaft and composed of an electrically conducting material at least in its peripheral zone, means for coupling said shaft with said cylinder, means on said cylinder for manual rotation of the same, said cylinder having a plurality of parallel peripheral grooves formed therein extending around said cylinder, contact balls to be fastened jammingly in the same, in different positions along the periphery corresponding to the instants of any desired switching operation, there being one groove for each 12-hour period, a slide movable in parallel with said cylinder and being displaceable step by step in response to the rotation of said cylinder, each step corresponding to the interspace between the individual grooves, and a counter-contact mounted on said slide for allowing contact balls to be jammed into said grooves, to engage said counter-contact in dependence upon the rotation of said cylinder.

11. A time-controlled actuating apparatus for performing electric switching operations, comprising, in combination, a clockwork having an hour-hand spindle, a shaft coupled with said spindle, a cylinder mounted rotatively on said shaft and being composed of a metallic material at least in its peripheral zone, means for coupling said shaft with said cylinder, means on said cylinder for manual rotation of the same, said cylinder having a plurality of parallel peripheral grooves formed therein, which grooves extend around the cylinder, a slide movable in parallel with said cylinder and being displaceable step by step in response to the rotation of said cylinder, each step corresponding to the interspace between the individual grooves, and contact means mounted on said slide to be actuated in dependence upon the rotation of said cylinder.

12. A time-controlled actuating apparatus for

performing electric switching operations, comprising, in combination, a clockwork having an hour-hand spindle, a shaft coupled with said spindle, a cylinder mounted rotatively on said shaft and being composed of a metallic material at least in its peripheral zone, means for coupling said shaft with said cylinder, means on said cylinder for manual rotation of the same, said cylinder having a plurality of parallel peripheral

10 grooves formed therein, which grooves extend around the cylinder and contact-controlling balls for jamming engagement in said groove in different positions along the periphery in accordance with the instants of any desired switching operation.

13. A time-controlled actuating apparatus for performing electric switching operations, comprising, in combination, a clock-work having an hour-hand spindle, a shaft coupled with said spindle, a cylinder mounted rotatively on said shaft and being composed of a metallic material at least in its peripheral zone, means for coupling said shaft with said cylinder, means on said cylinder for manual rotation of the same, 20 said cylinder having a plurality of peripheral grooves being formed therein which extend around the cylinder, contact ball for jamming engagement in said grooves, in different positions along the periphery of the cylinder in accordance with the instants of any desired switching operation, and a counter-contact in a position allowing contact balls jammed into said grooves to engage said counter-contact in dependence upon the rotation of said cylinder.

14. A time-controlled actuating apparatus for performing electric switching operations, comprising, in combination, a rotative timing cylinder composed of a metallic material at least in its peripheral zone, said cylinder having a plurality 25 of peripheral grooves, formed therein, which extend around the cylinder, and contact controlling balls for jamming engagement in said grooves, in different positions along the periphery in accordance with the instants of any desired switching operation.
